UNITED STATES PATENT OFFICE.

FRANK BUSATA MASUOKA, OF ROGERSON, IDAHO.

COMB CLEANER.

Application filed July 27, 1925. Serial No. 46,420.

To all whom it may concern:

Be it known that I, FRANK B. MASUOKA, a Japanese subject, residing at Rogerson, in the county of Twin Falls and State of Idaho, have invented new and useful Improvements in Comb Cleaners, of which the following is a specification.

This invention relates to sanitary devices and has for its object the provision of a novel device by means of which a comb may be quickly and easily cleaned.

An important and more specific object is the provision of a comb cleaning device embodying holding means for a continuous strand of cord or the like laced back and forth through the holding device and providing a plurality of lengths upon which the teeth of a comb may be engaged so that the comb may be moved back and forth to effect the removal of any accumulations between the teeth.

Another object of the invention is to provide a device of this character so constructed and arranged that the cord or string used for cleaning may be quickly and easily removed and replaced by a new one, it being of course highly desired that a fresh string be used for each comb cleaned.

A further object of the invention is to provide a device of this character particularly well adapted for use not only in the home but also in barber shops, beauty parlors and the like for the purpose of keeping the combs clean and in a thoroughly sanitary and satisfactory condition not only to comply with regulations which govern such establishments, but also to appeal to the taste of the customers.

Yet another object of the invention is to provide a device of this character provided with means in the form of a separate implement whereby a string or cord may be almost instantly properly engaged with the holding means, it being thereby unnecessary to thread the cord through the plurality of holding elements one by one, this resulting in a great saving of time.

An additional object is to provide a device of this character which will be simple and inexpensive in manufacture, easy to use, positive in action, efficient, sanitary and durable in service and a general improvement in the art.

With the above and other objects and advantages in view, the invention consists in the details of construction, and the arrange-

ment and combination of parts to be herein-after more fully described and claimed, and illustrated in the accompanying drawings, in which:—

Figure 1 is a perspective view of one form of the device showing the parts brought together and showing the act of effecting threading of the cord or string therethrough.

Figure 2 is a perspective view of the device in position ready for use.

Figure 3 is an elevation somewhat similar to Figure 1 showing a modified form of the invention, and

Figure 4 is an elevation similar to Figure 2, showing the modified form in position ready for use.

Referring more particularly to the drawings, and especially Figures 1 and 2, I have shown the device as comprising a pair of end members 10 and 11, the former of which is provided with a hole 12 and adapted to be engaged upon a supporting hook 13 or the like extending out from a wall or other support. The end member 11 is adapted to be held in the hand in the manipulation of the device as will be explained. In actual practice, these members 10 and 11 may very conveniently be formed as pieces of wood cut to the desired shape and provided at their ends with metal ferrules 14 and 15 respectively. The ferrule 14 is so formed as to provide beads 16 at the ends thereof within which are suitably secured the end portions of a wire coil 17 which may have its convolutions of any desired size. The ferrule member 15 is formed to provide beads 18 within which are engaged the end portions of a wire coil 19 similar to the coil 17.

In connection with these end members 10 and 11, I make use of a single length of cord or string indicated at 20 and I also make use of a particular implement for the purpose of threading this string through all of the convolutions of the wire coils 17 and 19. In effecting the threading action, one end of the string 20 is tied onto one end of the wire coil 17, as indicated at 21, and the string is then brought down alongside the handle member 11. Use is then made of an elongated tool 22 which may, in actual practice, be constructed as a single length of wire having one end formed with a finger grip 23 and its other end formed with a hook 24. The two wire coils 17 and 19 are brought together in interfitting relation as clearly

shown in Figure 1 and the tool 22 is inserted through all of them and manipulated so that the cord or string 20 will be caught within the hook 24. Subsequently to this, the operator pulls the member 22, carrying the string or cord 20 through all of the interfitting convolutions of the wire coil, and then moves the handle member 11 away from the end member 10 to the desired distance, after which the remaining end of the string or cord is tied onto one end of the endmost convolution of the wire coil 19, as indicated at 25. Obviously, when the member 11 is moved away from the member 10, the string engaged through all of the interfitting convolutions of the coil will be pulled out to define a plurality of parallel strands as clearly indicated in Figure 2. After the free end of the string or cord is tied at 25, or looped and hooked on to the free end of this coil, it is quite evident that by holding the handle member 11 in one hand and the comb to be cleaned in the other hand, and then rubbing the comb along the parallel strands of the string, which strands are indicated at 26, any accumulation of grease or other matter between the teeth of the comb may be very effectually and quickly removed. It is of course intended that a new string be used for each individual comb so that there will be no criticism as to the sanitary conditions.

In Figures 3 and 4 I have illustrated a slight modification in which the members 27 and 28 corresponding to the members 10 and 11 are formed as wire frames 29 and 30 respectively, the frames having looped portions 31 and 32 about which are engaged sheet metal plates 33 and 34 beaded or crimped onto the frames so as to remain permanently thereon. The member 27 is provided with a hole 35 whereby it may be engaged upon a nail, hook or other support as in the first described form.

Instead of using separate wire coils as in the first described form, the frames 29 and 30 are themselves formed with convolutions 35 and 36 respectively, which are adapted to be brought together in interfitting relation and in exactly the same manner as above described, whereby the string or cord may be introduced through them.

From the foregoing description and a study of the drawings, it will be apparent that I have thus provided a simply con-

structed, inexpensive and very satisfactory and durable device for the purpose specified, and one which will be a great saver of time, labor and annoyance especially where it is necessary to clean combs frequently. It is believed that the construction, operation and advantages will be readily apparent to one skilled in the art without further explanation.

While I have shown and described the preferred embodiment of the invention, it should be understood that I reserve the right to make such changes in the form, construction and arrangement of parts as will not depart from the spirit of the invention or the scope of the subjoined claims.

Having thus described the invention, I claim:

1. In a comb cleaning device, a pair of end members, one constituting suspension means and the other constituting a handle, each of said end members including a coil, the coil of one being adapted to be arranged in interfitting relation to the coil of the other and a flexible member detachably connected with one coil and adapted to be pulled through the interfitting coil whereby upon subsequent disengagement of the coils upon movement of the end members away from each other the flexible member will be caused to extend in laced relation between the end members to define a plurality of spaced parallel strands.

2. In a comb cleaning device, a pair of end members, one constituting suspension means and the other constituting a handle, each of said end members including a coil, the coil of one being adapted to be arranged in interfitting relation to the coil of the other, and a flexible member detachably connected with one coil and adapted to be pulled through the interfitting coil whereby upon subsequent disengagement of the coils upon movement of the end members away from each other, the flexible member will be caused to extend in laced relation between the end members to define a plurality of spaced parallel strands, in combination with a hook implement insertible through the interfitting convolutions of the coil whereby the flexible member may be drawn through preparatory to the separation of the end members.

In testimony whereof I affix my signature.

FRANK BUSATA MASUOKA,
